Attorney

UNITED STATES PATENT OFFICE.

HERMON E. CLEMONS, OF PULASKI, NEW YORK.

SPARK-PLUG.

1,398,175.

Specification of Letters Patent. Patented Nov. 22, 1921.

Application filed May 25, 1918. Serial No. 236,543.

To all whom it may concern:

Be it known that I, HERMON E. CLEMONS, a citizen of the United States, residing at Pulaski, in the county of Oswego and State 5 of New York, have invented certain new and useful Improvements in a Spark-Plug, of which the following is a specification.

This invention relates to new and useful improvements in spark plugs and the primary object of the invention is to provide a new and improved type of spark plug that has means for utilizing the heat generated during the operation of the engine, to keep the electrodes of the plug free from carbon 15 deposits, and hence, increasing the efficiency and durability of an article of this character.

Another object of the invention is to provide a device of this character which is 20 easily and simply constructed, inexpensive to manufacture, and one which will be very efficient in operation.

With these and numerous other objects in view, my invention consists of the novel features of construction, combination and arrangement of parts which will be herein referred to and more particularly pointed out in the specification and claims.

In the accompanying drawings:

30 Figure 1 is a vertical section through the spark plug,

Fig. 2 is a bottom plan view thereof,

Fig. 3 is a side elevation of the tubular terminal member that forms the heat retaining casing, and

Fig. 4 is a side elevation of the washer that retains the above mentioned member in position.

In describing my invention, I shall refer 40 to the drawings in which similar reference characters designate corresponding parts throughout the several views.

The numeral 1 designates an open ended outer casing which is provided with external 45 threads 2 on its lower outer end and the upper end thereof is provided with an inwardly projecting flange 3 for a purpose which will be hereinafter more fully described. The casing has mounted there- 50 through a non-conducting bushing 4 that is preferably formed of porcelain and which has one portion thereof designated by the numeral 5 projecting through the upper end of said casing.

The non-conducting bushing is provided 55 with an enlarged portion 6 disposed within the casing 1 adjacent its upper end, and the shoulder formed by the enlarged portion is adapted to bear against the flange 3 at the upper end of said casing, said parts being 60 separated by a gasket 7 as clearly shown in Fig. 1 of the drawings. The bushing 4 has positioned therethrough the central electrode or conductor of the plug which is designated by the numeral 8, said electrode projecting from the upper end of the bushing, and having the conventional type of jam nut positioned on the upper end that is adapted to bear against a compression nut 10 that is disposed on the upper end of said bushing. The opposite end of the electrode projects from the portion of the bushing disposed within the casing 1, and through said casing to a point beyond the lower end thereof as is clearly shown in Fig. 1 of the drawings. The electrode is provided with an enlarged portion 11 that is positioned within a recess 12 formed in the lower end of the bushing, for the purpose of which is obvious. 80

The heat retaining means that forms the improvement of this spark plug comprises a tube shaped secondary terminal 13, that is provided with an outwardly flared open upper end 14, said tube being adapted to be 85 positioned up through the lower end of the casing 1, and spaced from the inner wall thereof and having the flanged portion 14 bear against the lower shoulder of the enlarged portion 6 of the bushing. The tubular terminal will surround the lower end of the bushing and likewise the projecting portion of the electrode 8. This tubular terminal is held in position by an externally threaded washer member 15 that is adapted 90 for co-operative engagement with internal threads on the inner face of the casing adjacent the lower shoulder of the enlarged portion of the bushing, said washer bearing against the outer face of the flared portion 14 at the upper end of the tubular member, and adapted to hold the same against the lower shoulder of the bushing, as clearly shown in Fig. 1 of the drawings. The lower edge of the washer 15 is notched 100 105 as shown at 16 so as to facilitate the placing or removing of the washer in operative position.

The lower end of the tubular terminal 13 extends inwardly as shown at 17, and upwardly so that it surrounds the terminal 8 adjacent the lower extremity thereof. This 5 forms an opening through which the terminal is positioned, and the edges of the opening are disposed in close proximity to the terminal, so that a spark gap is formed between these parts. The lower end of the 10 tubular terminal is provided with a plurality of slits 18 preferably three in number, for a purpose to be hereinafter more fully described.

In operation, when the various parts of 15 the spark plug are disposed as is clearly shown in Fig. 1 of the drawings, upon the current passing down the electrode 8 it will cross the gap between the secondary terminal 13 formed at the lower contracted end 20 thereof, and up through said terminal out to the casing 1 as is obvious. Obviously, the passage of the heated gases through the tubular terminal will heat the same. The heated gases passing down through the slotted 25 lower end of the member will heat the lower portion of the plug and consequently will prevent the formation of carbon deposits between the terminals. The space between the lower terminal and the wall of the 30 tubular secondary terminal will form a heat chamber that will carry out the objects above described. The washer member 15 that holds the tubular terminal as well as the bushing within the casing of the spark plug, 35 owing to the fact that it requires a special tool for assembling or taking apart the plug, prevents the likelihood of the plug being damaged by unskilled hands, as where an external packing nut is used, and a hammer 40 and wrench are used to take the plug apart, which would be likely to damage the insulating bushing. This type of washer member

requires a special tool that is engageable with the notched lower edge thereof to remove the washer or place the same in position. 45

From the foregoing description taken in connection with the accompanying drawing, it is thought that a clear and comprehensive understanding of the construction, operation 50 and advantages of my invention may be had, and while I have shown and described the device as embodying a specific structure, I desire that it be understood that such changes may be made in said structure 55 as do not depart from the spirit and scope of the invention as claimed.

Having fully described my invention, what I claim as new, and desire to secure by Letters Patent, is: 60

A spark plug comprising an open casing, a non-conducting bushing projecting from one terminal of the casing having an enlarged portion confined within the casing, a center electrode carried by the bushing, 65 a tubular member positioned within the lower end of the casing and spaced from the inner wall thereof and having an outwardly directed flange at its upper terminal bearing against the enlarged portion of the bushing and constituting a gasket therefor, a washer screw threaded in the casing and bearing against the flared terminal of the tubular member to hold the latter and the bushing in position, notches formed on said 70 washer for removing the same from the casing, and thereby releasing the tubular member, and inwardly directed integral fingers carried by the tubular member terminating in spaced relation to the center electrode to provide a spark gap. 75

In testimony whereof I affix my signature. hereto.

HERMON E. CLEMONS.
